TOP GLUER.

1,423,567.

Specification of Letters Patent. Patented July 25, 1922.

Application filed February 6, 1920. Serial No. 356,703.

To all whom it may concern:

Be it known that we, LEON E. LA BOMBARD, a citizen of the United States, and resident of Chelsea, in the county of Suffolk, State of Massachusetts, and MELVIN H. SIDEBOOTHAM, a citizen of the United States, and resident of Cliftondale, in the county of Essex and State of Massachusetts, have invented certain new and useful Improvements in Top Gluers, of which the following is a specification.

This invention relates to devices for applying an adhesive substance, hereinafter referred to generically as glue, to articles such as foldable paper or pasteboard blanks, and the invention has particular reference to devices of this character which are mounted as attachments to box folding machines to supply stripes or bands of glue to surface portions of blanks while the latter are on their way from a feeding mechanism to folding mechanism. Such devices usually employ a thin wheel or disk to apply the glue to the passing blanks, and in the majority of machines the blanks are carried over the glue wheel or disk so that a stripe of glue is applied to the under surface of each blank. As will be readily understood the construction of a practical gluer having the upper portion of its wheel exposed to apply glue to the under surfaces of blanks passing over it presents no problem that is difficult to solve. This is because it is entirely feasible to have an ample portion of the wheel revolve in a body of glue in a box and employ a scraper to remove excess of glue from the wheel. But when a machine is to be constructed to operate on blanks which require the application of glue to upper surface portions thereof, a serious problem arises as to how to keep a wheel properly supplied with glue so that its periphery will transfer the right amount, and only the right amount, to blanks passing under it. Attempts have been made to provide devices of this kind and they are called top gluers because they coat or stripe top surfaces instead of under surfaces of passing articles. So far as we are aware such attempts have not proved entirely satisfactory for several reasons such as failure to prevent leakage of glue and inability of the wheel or disk to perform uniform work on the blanks.

The object of the present invention is to provide a simple and reliable device having a rotary applicer to which an easily controlled supply of glue can be furnished and maintained without leakage, and yet permit the lowermost portion of said applicer to be exposed for contact with articles passing below it. Several features of novelty which constitute our invention contribute singly or jointly in attaining said objects, and said features will now be described and then pointed out in the appended claims.

Of the accompanying drawings:

Figure 1 is a perspective view of the entire top gluer.

Figure 2 represents a detail section omitting some parts.

Figure 3 represents a detail section at a right angle to Figure 2.

Figure 4 is a broken out detail perspective view.

Figure 5 is a perspective view of the lower end of the glue pot or reservoir.

Figure 6 is a detail sectional elevation to illustrate how the control of the film of glue on the wheel is effected.

Similar reference characters designate similar parts in all of the views.

The support for the device consists of a column or post 12 which is fixed in position in that part of a machine which is best suited to accommodate the gluer. It is to be understood that in a machine for making flat folded boxes the post and gluer are located so that the disk or wheel 13 thereof will apply a stripe or line of glue to the top surface of each of a succession of blanks carried from the feeder to the folding mechanism in the direction of the arrow *a* in Figure 1 and in a plane tangential to the lowermost portion of the periphery of the disk. Said wheel 13 is carried by a shaft 14 mounted in a bearing provided in a split block 15 having a sleeve portion fitting the post 12 and adapted to be clamped in vertically adjusted position on the post by a screw 16.

The shaft 14 and its disk 13 are driven in the direction indicated by arrows in several figures by suitable means such as a driving chain 17 engaging a sprocket 18 fixed to the shaft.

A bracket 19 having a split sleeve portion fitting the post 12 below the block 15 is

adjustably secured to the post by a clamp screw 20. The outer end of the bracket (Figs. 2 and 3) is formed to provide a bearing 21 for a pintle 22. A shallow cup 23 has two ears 24 which extend past the ends of the bearing 21. The pintle passes through the ears 24 and is held by one or more screws 25. The structure just described provides a hinge connection between 10 the cup and bracket which, while providing for separation by removing the pintle when the cup is to be cleaned, holds the cup steadily in use. The reason for the hinge connection will be presently explained.

15 At substantially the center of the bottom of the cup 23 is a screw threaded recess 26 to receive a screw stem 27 projecting down from the bottom of the glue pot or reservoir 28 which is air tight except for one or more 20 holes 29 in its bottom. Rotatable on the screw stem 27 is the hub 30 of a strip 31 (Fig. 5), said strip being held close to the bottom of the reservoir by a screw 32 (Fig. 3) entering an annular groove in stem 27. 25 The strip is provided with one or more upturned ears 33, either one of which may be grasped as a handle to turn the strip one way or the other on the stem 27 to open or close the holes 29. Projecting down from 30 the bottom of the reservoir is a stop lug 34 (Fig. 5) in such position that when one portion of one edge of the valve strip 31 contacts with the lug the holes will be closed and when another portion of the same edge 35 contacts with the lug the holes will be uncovered.

Attached to one side of the cup 23, preferably by screws 35 so it can be removed for cleaning (Figs. 2 and 4) is a narrow trough 40 36, the adjoining walls of the cup and trough being cut away so glue in the cup may flow into the trough. Secured to one end of the trough is a slotted gage 37 which so closely fits the sides of the disk 13 that 45 glue will not escape freely between the gage and the disk. When the disk rotates however sufficient glue is carried out by its periphery to supply the necessary adhesive to a blank fed by the usual belts, not necessary to illustrate, in a path or plane just 50 below the bottom of the trough.

Owing to the fact that the slot in the gage 37 closely fits the sides of the disk, and that said slot is in an upright wall of 55 the trough, and that the glue in the trough is automatically limited to a depth which can not exert such pressure outwardly as to cause glue to be carried out on the sides of the disk, the width of the stripe of glue 60 transmitted to passing blanks is rendered reliably uniform, and said stripe is free from thick edges. In other words the stripe of glue transmitted to the blanks is practically uniform in thickness as well as in 65 width and consequently is not liable to be

unduly broadened by the pressure which is later exerted on the blanks while they are being folded and converted into boxes. The thickness of the film of glue carried out on the periphery of the disk is controlled by 70 the distance of the bottom of the slot in the gage 37 from the disk, and said distance is increased or diminished by lowering or raising the gage. As the gage is carried by the trough and the latter is carried by the hinged cup 23, adjustment of the latter by suitable means such as a screw 75 38 (Fig. 2) enables a fine adjustment to be effected to permit the periphery of the disk to carry out the desired amount of glue. 80

Another means for effecting a variation in the space between the bottom of the slot and the periphery of the disk for the purpose just mentioned, consists in the independent mounting of the block 15 and the 85 bracket 19 on the post 12 (Fig. 2) so that either can be vertically adjusted as hereinbefore described. By the employment of the screw 38 however, a finer adjustment can be effected. 90

When the device is to be employed, the glue pot is removed and reversed and filled through one of the holes. Then the valve strip 31 is turned to close both holes 29 and the pot is set in the position shown in 95 Figure 3 by securing its screw 27 in the cup recess 26. Upon then swinging the strip 31 by means of one of its ears 33 so as to uncover the holes 29, glue will flow out into the cup and the trough to the level of the bottom 100 of the pot when, no more air being admitted to the pot, the outflow of the glue will cease. As the general principle of similar devices for preserving a liquid at a certain level is well known no further description 105 will be necessary for an understanding of why the glue will remain in the trough at a practically uniform level.

If the adhesive to be employed is of a kind which must be used, warm or hot, any 110 suitable means not necessary to illustrate may be employed for heating the cup and reservoir. The glue which is usually employed, whether hot or cold, for adhesively connecting overlapping parts of paper 115 boxes, is not a readily flowing liquid. Its consistency is such that the disk 13 is able to serve as a dam for the slotted exit in the gage 37. Exudation of the glue is prevented from being faster than it is drawn 120 out by the periphery of the revolving disk. This is because there is no material pressure of glue seeking to escape through the slot of the gage. Such would not be the case however if the glue were subject to the pressure of a body of glue extending to a considerable height so as to tend to force glue 125 out onto the sides of the disk. To permit the disk to serve the double purpose of an applier and a dam is the chief reason for 130

employing the shallow trough 36 and means for limiting the depth of glue in said trough.

When the machine employing the gluer 5 is stopped or is about to be stopped, the strip 31 will be turned to close the holes 29. After this the reservoir can be removed for filling, or to facilitate access to the other separable parts for cleaning. If the machine is simply 10 to be stopped for a time and there is such a space between the edge of the disk and the bottom of the slot in the gage as would permit glue to exude, that space can be entirely closed by operating the screw 38 to 15 crowd the bottom of said slot close to the edge of the disk.

To enable the machine to be started at any time, without delay, even if glue has hardened on the sides of the disk 13, we provide 20 a sharp-edged scraper 39 on each side of the disk. In the embodiment of the invention illustrated these scrapers are provided by vertically grooving the inner face of the gage 37 the side of each groove nearest the 25 disk being bevelled to provide a form of knife edge close to the disk. Therefore, when the disk revolves in the direction of the arrows in Figs. 1 and 4, glue removed by the knife-edge scrapers 39 flows down the 30 grooves, and if that glue is hardened it mingles with glue in the trough and is softened.

It is to be understood that if the glue 35 is of a kind which requires heat to make it mobile, any suitable means will be provided to heat the pan and trough.

Having now described our invention, we claim:

1. A device of the character described 40 comprising a glue holder having a slotted end wall, means for continuously supplying a limited amount of glue to said holder, and a rotary applier a portion of which substantially fills the slot of said wall, means being 45 provided for preventing glue from being carried out of the holder on the sides of the applier.

2. A device of the character described 50 comprising a glue holder having a slotted end wall, means for continuously supplying a limited amount of glue to said holder, and a rotary applier a portion of which substantially fills the slot of said wall, another portion 55 of the applier extending to a plane below the plane of the bottom of the holder, means being provided for preventing glue from being carried out of the holder on the sides of the applier.

3. A device of the character described 60 comprising a glue trough having a slotted end wall, means for continuously supplying a limited amount of glue to said trough, and a rotary disk a portion of which extends into the slot of the wall, said disk being 65 mounted relatively to the trough to present

its lower portion below the plane of the bottom of the trough.

4. A device of the character described comprising a glue trough having a slotted end wall, means for continuously supplying 70 a limited amount of glue to said trough, and a rotary disk a portion of which extends into the slot of the wall, said disk being mounted relatively to the trough to present its lower portion below the plane of the bottom of the 75 trough, means being provided to keep the trough supplied with glue to a predetermined level.

5. A device of the character described comprising a glue trough having a slotted 80 end wall, means for continuously supplying a limited amount of glue to said trough, a rotary disk a portion of which extends into the slot of the wall, said disk being mounted relatively to the trough to present 85 its lower portion below the plane of the bottom of the trough, and means for adjusting the relative positions of the disk and slot.

6. A device of the character described 90 comprising an upright, a glue trough adjustably mounted on said upright, and a rotary glue applier adjustably mounted on the upright independently of the trough.

7. A device of the character described comprising a rigid upright, two brackets adjustably mounted one above the other on said upright, a rotary disk carried by one bracket, and means carried by the other bracket for supplying the disk with glue. 100

8. A device of the character described comprising a rigid upright, two brackets adjustably mounted one above the other on said upright, a rotary disk carried by one bracket, a trough for supplying glue to the 105 disk pivotally connected with the other bracket, and means for adjusting said trough.

9. A device of the character described comprising a cup, a trough having a slot in 110 one end wall, said trough communicating with the cup, a rotary disk partially located in and closely fitting said slot, and means for adjusting the relative vertical positions of the trough and disk to vary the space 115 between the bottom of said slot and the periphery of the disk.

10. A device of the character described comprising a cup, a trough having a slot in one end wall, said trough communicating 120 with the cup, a rotary disk partially located in and closely fitting said slot, and means for supplying the cup and trough with glue to a predetermined level.

11. A device of the character described 125 comprising a cup, a trough having a slot in one wall, said trough communicating with the cup, a rotary disk partially located in said slot, and a glue reservoir removably mounted in said cup, said reservoir having 130

- an opening in its bottom and being otherwise air-tight.
12. A device of the character described comprising a cup, a trough having a slot in one wall, said trough communicating with the cup, a rotary disk partially located in said slot, and a glue reservoir removably mounted in said cup, said reservoir having an opening in its bottom and being otherwise air-tight, a manually operable valve being provided for said opening. 25
13. A device of the character described comprising a cup, a trough removably connected thereto and communicating therewith, said trough having a slot in its end wall, a rotary disk partially located in and closely fitting said slot and mounted to present its lower edge below the plane of the bottom of the trough, and means for supplying the cup and trough with glue to a predetermined level. 30
14. A device of the character described comprising a hingedly supported cup, means for supplying the cup with glue, a trough communicating with the cup and having a slotted wall, a rotary disk partially located in the wall slot of the trough, and a screw for adjusting said cup, said screw being in position to vary the distance between the edge of the disk and the bottom of said slot. 35
15. A device of the character described comprising a glue holder having a slotted wall provided with scrapers along the margins of the slot, and a rotary applier a portion of which substantially fills said slot. 40
16. A device of the character described comprising a glue holder having a slotted vertical wall and formed with grooves adjacent the sides of the slot, the sides of the grooves being bevelled toward said slot to form knife-edge scrapers, and a rotary applier traversing said slot. 45

In testimony whereof we have affixed our signatures.

LEON E. LA BOMBARD.
MELVIN H. SIDEBOOTHAM.
